Inventor:
Arnold Heitink Jr.
by Dring & Heagel Atty's.

UNITED STATES PATENT OFFICE.

ARNOLD HEITINK, JR., OF OSKALOOSA, IOWA.

CHURN.

Application filed April 3, 1923. Serial No. 629,620.

To all whom it may concern:

Be it known that I, ARNOLD HEITINK, Jr., a citizen of the United States, and a resident of Oskaloosa, in the county of Mahaska, State of Iowa, have invented a certain new and useful Churn, of which the following is a specification.

The object of my invention is to provide a churn of the class designed for home use and to be hand operated, and particularly of the class intended to be used in connection with relatively small quantities of cream.

My object is to provide a churn of this character of simple, durable and inexpensive construction and of few parts so arranged that they may be readily, easily and quickly assembled for use or taken apart for cleaning or storing; and

20 A further object is to provide a churn of this character in which, during its operation, no cream will be thrown out of the churn or in contact with the screw cap of the churn, so that the operation of the churn can be 25 easily and conveniently carried on upon the kitchen table or the like, and after the churning operation has been completed, the parts may be taken apart and cleaned with a minimum of work.

30 My invention consists in the construction, arrangement and combination of the various parts of the device, whereby the objects contemplated are attained, as hereinafter more fully set forth, pointed out in my claim, and 35 illustrated in the accompanying drawings, in which:

Figure 1 shows a side elevation of my improved churn assembled ready for use.

Figure 2 shows a vertical, central, sectional view through the upper portion of the churn body to illustrate the operative parts; and

Figure 3 shows a top or plan view of the bowl shaped anti-splasher device.

45 Referring to the accompanying drawings, I have used the reference numeral 10 to indicate the churn body which is preferably made of glass, and the interior is rounded and without corners. It is formed with a 50 base 11 preferably integral with the glass body and with a large opening at its top screw threaded on the exterior.

Mounted upon the top of the base is a screw cap 12 having its central portion provided with a bearing 13.

The reference numeral 14 indicates a gear

case preferably made of cast metal closed at its top and sides and open at its under side, and containing a vertical shaft 15 mounted in a bearing 16 and provided at its upper 60 end with a beveled pinion 17. The lower end of this shaft is formed hollow and a set screw 18 is mounted therein.

Within the gear case 14 is rotatably mounted a crank shaft 19 in the bearings 20 65 and 21, and on this shaft is a beveled pinion 22 in mesh with the beveled pinion 17. This gear case is supported upon the screw cap 12 by means of legs 23, which legs are preferably formed integral with the gear case 70 and both contained in the screw cap. By this means considerable separation is provided between the screw cap and the gear case so the operator may readily have access to the set screw 18.

75 The reference numeral 24 indicates a dasher which is preferably formed of a single piece of wood with one blade extended upwardly and the other blade extended downwardly and both blades provided with 80 perforations. This dasher is mounted upon a shaft 25 which extends through a part of the dasher and held firmly to the dasher by means of nuts 26, or in any suitable way.

85 The reference numeral 27 indicates an anti-splasher device preferably of substantially hemispherical shape and made of glass. It is provided at its central portion with an opening 28, and around its upper edge with an outwardly extended flange 29. 90 This flange is of such size and shape that it may be readily inserted in the bottom of the screw cap and made to rest upon the top of the neck of the churn body, and between the flange 29 and the top of the body I preferably provide a rubber gasket 30. The opening 28 is of such size that the shaft 25 is free to pass through it and turn around within said opening without touching any part of the glass anti-splasher device.

100 In practical use the cream is first placed within the churn body and then the dasher and its shaft is placed in the cream. Then the gasket 30 and the anti-splasher device are placed in position with the shaft 25 projected through the opening 28. Then the screw cap is firmly screwed to the top of the body to form a tight joint, thus clamping the anti-splasher device firmly in position and centering it so that its opening 28 will 110 be centered relative to the shaft 25. Before applying the screw cap, the upper end of

the shaft 25 is passed through the bearing 13 in the screw cap, then the operator grasps the upper end of the shaft 25 and inserts it in the lower end of the shaft 15 and secures it in this position by the set screw 18, whereupon the device is ready for use; and when the crank 19 is manipulated, the dasher will be rapidly rotated within the churn body.

10 During such rotation it is well known that the cream will be splashed upwardly and in all directions within the body. However, by the use of my improved anti-splasher device only a very small quantity of the cream 15 will pass up through the opening 28, and such quantities of the cream as do pass through, will not go up so far as to engage the under-surface of the screw cap, but will at once drain out of the opening 28 back into 20 the churn body.

After the operation of churning has been completed, the operator first releases the set screw 18, then removes the screw cap and then grasps the upper end of the shaft 25 and draws the dasher and also the glass 25 anti-splasher device upwardly out of the churn. The screw cap and the parts permanently connected to it will be found to 30 be free from any cream and can be stored away without washing. The dasher and its shaft and the anti-splasher device may then be placed in a suitable receptacle and

washed in the ordinary manner, and the interior of the churn may be readily and easily cleaned because all of the parts may 35 be conveniently and easily reached by the operator as there are no corners.

I claim as my invention:

In a device of the class described, the combination of a body formed with an opening at its top, a combined cover and support detachably fixed on top of the body and having its top surface shaped and designed to support an agitator operating mechanism, an agitator shaft extended through 45 said cover and supported and designed to be detachably connected to the agitator operating mechanism carried by the shaft, and a splash device substantially hemispherical in shape and having an outwardly extending flange at its top designed to be inserted 50 between the top of the body portion and the under surface of said cover and support, said splash device having an opening in its bottom for the agitator shaft and being otherwise completely enclosed to prevent any of the contents of the body from splashing 55 against any part of the cover and support, and whereby the cover and support may be readily and easily removed from the body and the agitator shaft, for the purposes stated.

Des Moines, Iowa, March 13, 1923.

ARNOLD HEITINK, JR.
